CLAIM

The ornamental design for a combined pointing device and coupling assembly, as shown and described.

DESCRIPTION

FIG. 1 is an isometric view of a combined pointing device and coupling assembly showing our new design; FIG. 2 is a rear elevational view thereof; FIG. 3 is a top plan view thereof; FIG. 4 is a bottom plan view thereof; and, FIG. 5 is a left side elevational view thereof, the right side is a mirror image.
